MACHINE FOR SEPARATING WOOL FIBRES OR OTHER FILAMENTS

Arpad Boer, Buenos Aires, Argentina, assignor, by mesne assignments, to Bancroft-Brillotex International S.A., Montevideo, Uruguay, a corporation of Uruguay

Application April 27, 1955, Serial No. 504,320

1 Claim. (Cl. 19—131)

The present invention relates to a machine for drafting wool and other fibers and more particularly to a machine having a series of pairs of endless belts arranged linearly to form a treatment path for the fibers and operating at successively higher speeds over rolls on which they are mounted and by which they are driven, said endless belts being provided with spaced raised strip-like sections with intermediate grooves and said raised sections diminishing in width in succeeding belts to provide a decreasing size gradient in the direction of travel of the fibers through the machine.

The machine of the present invention has advantages over other machines for the present purposes in that it is simple and effective and produces unusually good results without permitting felting of the fibers and representing more than a mere mechanization of operations previously carried out manually, in which latter connection the fibers can be subdivided by the machine to an extent not possible manually due to the size of the fingers.

For example, there are two ways of separating the fibers of sheared fleece. One way is to separate the fibers by lateral movements and the other is to thin them out. The former gives rise to felting of the fibers and the latter cannot provide the desired extent of subdividing.

The new machine, however, is very effective in thinning out and separating the fibers and in progressively processing the fibers by successively diminishing active belt areas to obtain maximum subdivision amounting to substantially a total separation of the fibers which are discharged from the machine practically as individual parallel fibers. These results are obtained by a special belt construction in combination with an increasing speed gradient of successive belts and the provision of successively narrower active raised sections on the series of belts, as hereinafter more fully described. These raised sections extend in the direction of fiber movement and are provided on either one or both of the belts of each pair of belts.

In the accompanying drawings:

Fig. 1 is a front elevational view, with parts broken away, of a machine embodying the invention;

Fig. 2 is a profile view of Fig. 1 showing, by means of increasing directional arrow lengths, the progressively higher speeds of successive pairs of belts;

Fig. 3 is a plan view of Fig. 1 showing the use of one belt with raised sections and one smooth surfaced belt;

Fig. 4 is a plan view similar to Fig. 1 of a modified form of the invention wherein both belts of each pair are provided with raised sections; and

Fig. 5 is a schematic view showing diagrammatically the progressive thinning out and subdividing of the fibers as carried out by the machine.

Referring now to the drawings in detail, the machine comprises a plurality of pairs of endless belts $b-b'$ mounted on and driven by rolls 3, 4 whose axes 1, 2, respectively, are journaled in longitudinal side frames a . The belts are stretched over the sets of rolls to provide the desired tensioning of the belts in a manner well understood. Means of any suitable or conventional

2

nature is provided for driving the rolls, and hence the belts, in such manner that each succeeding pair of belts travels over its rolls at a higher rate of speed than the preceding pair of belts from the entrance end of the machine to the discharge end, as indicated by the progressively longer directional arrows in Fig. 2. At the entrance end of the machine, there is a pair of feed rolls $c-c$, also journaled in frames a , which receive and grip the fibers 5 and pass them to the first pair of endless belts $b-b'$. These rolls $c-c$ operate at a slower rotational speed than the rolls of the first pair of belts.

The pairs of belts $b-b'$ and the rolls $c-c$ are arranged in a linear series to form a treatment path or channel and portions of the belts are parallel as will be seen in Fig. 2. There is thus formed an increasing speed gradient along the machine.

At least one belt of each pair is provided on its active surface across its width with spaced raised strip-like sections 7 which extend in the direction of travel of the fibers 5 and which alternate with grooves 8. In the form of the invention shown in Figs. 1-3, only one belt of each pair is so configured, the other belt of the pair being smooth, whereas in the modified form of the invention shown in Fig. 4 both belts of each pair are provided with the raised sections and the raised sections of one such belt coincide with the raised sections of the other belt to provide gripping surfaces for the fibers. The grooves also have some but much less gripping effect and provide a retarded impellance of the fibers as compared to the action of the raised sections.

As will be clear from Fig. 1, the raised sections and grooves of each succeeding belt or pair of belts are of less width than the raised sections and grooves of each preceding belt or pair of belts, thus providing a decreasing size gradient with respect to the width of the raised sections and grooves in the direction of the discharge end of the machine. This arrangement in combination with the increasing speed gradient provides a unique machine capable of effectively bringing about the processing of the fibers according to the invention.

Operation

The operation of the machine will be understood from the construction thereof taken with the diagrammatic showing of Fig. 5.

Wool, hair or other fibers such as shorn fleece are fed into the machine in such manner that the fibers are approximately parallel to their direction of travel through the machine. This is effected by rolls $c-c$ operating at minimum speed which pass the fibers to the first pair of endless belts $b-b'$, either or both of which are provided with the raised sections and grooves above described, which grip the fibers and pass them between succeeding pairs of belts, each passage being at a higher speed than the previous one. Drafting and subdividing of the fibers occurs progressively and in proportion to the increasing speed gradient and the decreasing width of the raised sections and grooves. The portions of the fibers acted on by the raised sections advance more rapidly than those portions acted on by the grooves which exert a reduced impellance and a dragging action as compared to the raised belt sections. Passage of the fibers from one pair of belts to the next until the last pair of belts acts on the fibers produces the drafting, thinning and subdividing of the fibers which are discharged from the machine practically as separate individual parallel filaments. The action may also be considered as defibering.

It is to be understood that the foregoing is intended as illustrative and not as limitative since various modifications may be made in the details of construction without departing from the invention as defined by the appended claim.

I claim:

A machine for drafting wool and other fibers, comprising a series of pairs of endless belts the belts of each pair being face to face and the pairs of belts being arranged linearly to form a treatment path from the entrance end of the machine constituted by the first of such pairs of belts to the exit end of the machine constituted by the last of such pairs of belts, said endless belts being mounted on and driven by rolls mounted in bearings, the active outer surfaces of at least one of the belts of each pair being provided across their width with a plurality of spaced raised strip-like sections with intermediate grooves, the raised sections and grooves extending in the direction of fiber movement, the raised sections and grooves of each preceding pair of belts being of greater width than the raised sections and grooves of each succeeding pair of belts, so that the series of pairs

of belts forms a decreasing size gradient with respect to the widths of the raised sections and grooves of their surfaces, means for driving the rolls of the pairs of endless belts at successively increasing speeds so that from the first pair to the last there is formed an increasing speed gradient, whereby successive belts, with their raised sections, are capable of drafting the fibers supplied from preceding belts, while, due to the decreasing size of the width of the raised sections, the series constitutes a progressive fiber subdivider.
